(57) CLAIM

The ornamental design for a paint brush sleeve, as shown and described.

DESCRIPTION

FIG. 1 is a perspective view of a paint brush sleeve showing the new design.

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof; and,

FIG. 8 is a perspective view showing the paint brush sleeve in an example environment.

The portions of the drawings shown in short-dashed lines form no part of the claimed subject matter.
